Primary Examiner — Mary Ann Calabrese(74) *Attorney, Agent, or Firm* — Troutman Pepper Hamilton Sanders LLP(57) **CLAIM**

I claim the ornamental design for a table, as shown and described.

DESCRIPTION

FIG. 1 is a top, front perspective view of a table; FIG. 2 is a bottom, rear perspective view of the design shown in FIG. 1;

FIG. 3 is a front plan view of the design shown in FIG. 1; FIG. 4 is a rear plan view of the design shown in FIG. 1; FIG. 5 is a left side plan view of the design shown in FIG. 1;

FIG. 6 is a right side plan view of the design shown in FIG. 1;

FIG. 7 is a top plan view of the design shown in FIG. 1; and, FIG. 8 is a bottom plan view of the design shown in FIG. 1. The broken lines illustrate portions of the table that form no part of the claimed design.
